HANK TWISTING MACHINE

Emile Bernard Bates, Leicester, England

Application December 1, 1951, Serial No. 259,331

Claims priority, application Great Britain
December 4, 1950

13 Claims. (Cl. 57—25)

1

This invention concerns a machine for twisting hanks of yarn or thread (which expressions are employed herein as being synonymous) and for reducing the same to more compact form.

The machine provided by this invention comprises two spaced holders for the reception of the hank, means for effecting relative rotation between them to twist the hank and to produce a loop or eye in one end of the twisted hank, and means for doubling the twisted hank on itself to bring it end to end and for inserting the other end through the eye. Thus the hank is reduced to a comparatively compact form in which it is more easy to handle.

The last said means preferably operates by bringing the two holders into proximity, and specifically the holder for the said other end may move into a position in which it is disposed at the inside of the holder for the eye-end of the hank so that it enters the eye.

The doubling operation is facilitated by the provision of a stop arranged to engage the twisted hank in the region of its mid length.

According to an important subsidiary feature of the invention mechanism is provided for varying at will the number of twists imparted to the hank. According to another important feature of the invention mechanism is provided for adjusting the spacing between the two holders to accommodate them to hanks of differing sizes.

The foregoing and other features of the invention set out in the appended claims are incorporated in the hank twisting machine which will now be described by way of example, with reference to the accompanying drawings in which

Figure 1 is a perspective view of the machine;

Figure 2 is a plan view of certain of the mechanism therein;

Figure 3 is a sectional elevation showing the power drive for the machine;

Figures 4, 5, and 6 are sectional elevations of details of the mechanisms, taken respectively on the lines IV, V, and VI in Fig. 2;

Figure 7 is a perspective view of part of the mechanism for moving the stop into and out of operative position;

Figure 8 shows a belt-tensioning device employed in the power drive;

Figures 9, 10 and 11 are perspective views showing successive stages in the twisting of a hank.

This machine comprises two holders 1, 2, normally spaced apart, holder 1 being mounted on a spindle 3 for rotation and holder 2 being carried on the outer end of arms 4 that are pivoted to swing about the axis of a shaft 5 substantially

2

midway between the two holders. In general the shaft 5 is horizontal and the holders in their rest position are directed upwardly as shown in Fig. 1. Therefore for convenience in the ensuing description this arrangement will be assumed.

The holder 1 comprises an upstanding element 6 which in plan is of arcuate form presenting its convexity away from and its concavity 7 towards the other holder 2. The latter consists of an upstanding finger or horn having a lateral protrusion 8 at a suitable distance below its tip and directed away from the first holder. The arrangement is such that a hank of yarn 9 may be slipped on to and stretched between these two holders, its descent being limited on the one hand by the protrusion 8 and on the other hand by suitable stop 10 associated with the first holder.

Mechanism is provided for rotating the first holder 1 and its spindle 3 about the axis of the latter. Thus the hank 9 is twisted into a rope, the axis of which is substantially co-incident with the extended axis of rotation as shown in Fig. 9. Owing to the shape of the first holder 1 and to its width in a direction transverse to said axis it acts as a spreader to hold the hank open at this end so that an eye 11 is formed in the hank.

After the hank has been twisted to the appropriate extent the arms 4 on which the second holder 2 is supported are swung up and over through approximately 180° about the horizontal axis of shaft 5 which is disposed substantially midway between the initial positions of the two holders. Matters are so arranged that towards the end of this movement the second holder 2 moves down the concave side 7 of the first holder 1 and so enters the eye 11 in the hank 2 (see Fig. 10). The protrusion 8 passes down through a key-hole slot 64 in a base plate or stop 10 of holder 1, carrying the associated end of the twisted hank into the eye 11.

In the foregoing operation the hank is doubled on itself, and this is assisted by the provision of a stop 12 which is located substantially midway in the length of the hank and is in the form of a horizontal peg. The arrangement is such that as the second holder swings upwards the hank engages the underside of this peg 12 and is folded over it.

Finally the second holder 2 rises to disengage from the hank and swings back to its original positions, and the hank is then discharged from the first holder 1 and from the stop or peg 12 just mentioned.

This discharge is effected by means of a device 13 preferably consisting of a series of fingers

fixed on a shaft 14 and rotatable between the position shown in Figs. 1, 9, and 10, and the position shown in Fig. 11. It will be seen that this device 13 sweeps the twisted hank off the element 5 and off the holder 2 on to a table 15.

It is desirable to provide means for adjusting the initial spacing between the two holders 1, 2. This may be achieved by shifting the two holders towards or away from each other to equal extents or by shifting one holder only. In the accompanying drawings the holder 2 is mounted on parallel telescopic arms 4 which are adjustable for length. It is carried by a cross bar 16 which connects the free ends of the two arms 4 and protrudes beyond one side thereof so that the holder 2 is offset to one side of the arms.

If it is desired also to adjust the position of the holder 1 this holder may be carried in a head stock which is adjustable along the axis of rotation or for example the spindle 3 may be adjustable for length.

Turning now to the means for producing the various twisting and casting off movements already described, power is derived from a suitable source such as electric motor 17 and is applied through belt tensioning mechanism 18 controlled by a control device 19 to a reduction unit 20 and thence to a pulley 21 on a shaft 22. This shaft 22 carries a gear wheel 23 which it drives through a friction clutch 24; the gear wheel 23 drives pinion 25 on the shaft 3. Thus so long as the gear wheel 23 is rotated, the shaft 3 and the device 1 are rotated also.

The shaft 22 also carries a pinion 26 meshing with a gear wheel 27 on a counter-shaft 28 extending lengthwise of the machine. This shaft 28 is therefore continuously driven and it carries a series of cams 29, 30, 31 which produce certain of the twisting motions as hereinafter described.

It is desirable to provide means by which the number of turns imparted to the hank may be varied at will and means by which the rotation of the holder 1 shall be confined exactly to a whole number of revolutions so that the element 6 always stops in the upright attitude. On the shaft or spindle 3 there is a stop member 32 which is adapted to be engaged by the end of a lever 33, pivoted at 34, when this lever is dropped into the position shown in Fig. 3. When this happens the friction clutch 24 is caused to slip and the shaft 3 is held stationary with the element 6 upright. The lever 33 is held up and is permitted to drop at the proper time by the following mechanism. On the end of shaft 28 there is a member 35 having a number of holes 36 for the removable reception of pegs 37. Any number of pegs may be inserted. Their function is, of course, to lift the lever 33 to inoperative position and to hold it lifted for the proper time. A single peg permits of two rotations of the holder 1 and each succeeding peg permits of one further rotation.

Turning now to the various cams on the cams shaft 28, these and their associated mechanism are shown in greater detail in Figures 4, 5, and 6. Cam 29 operates the hank-discharging device 13. It is disposed to engage a chain, cable or the like 38 which extends over sprockets, pulleys, or the like 40, 41 (the latter being on shaft 14) between an anchorage 42 and a return spring 43 which is attached to anchorage 44. Thus when the cam 29 deflects the flexible element 13 the spring 43 is extended and the discharge device 13 is swung to its Figure 11 position. Immediately afterwards to the pull of the spring 43 effects the return of said device 13 to its Fig. 1 position.

Cam 30 serves to produce the movements of the holder 2. It serves to rock a truck lever 45 pivoted at 46 and connected to one end of a chain, cable or the like 47 which extends over sprockets (or their equivalent) 48, 49, and has its other end connected by a return spring 50 to an anchorage 51. The sprocket 49 is mounted on the spindle 5 on which the carrier 2 is supported. Thus when the cam 30 depresses lever 45 the chain or the like 47 is pulled and the spindle 5 is rocked to swing the carrier 2 from the position shown in Figs. 1 and 9 to that shown in Fig. 10. When the cam permits lever 45 to ascend the spring 50 asserts itself and the carrier 2 is swung back to its Fig. 1 position. Desirably, the carrier 2 is provided with a balance weight 52 so that it swings easily between its two positions.

Cam 31 serves to rock the table 15 periodically about an axis 53 so that immediately after a hank has been received on the table the latter is tilted to cause the hank to slide to the back. The cam 31 also serves to shift the stop peg 12 into and out of operative position. It will be seen from Figs. 6 and 7 that the stop peg 12 is carried on a lever 54 pivoted at 55 in a carrier 56. A cable 57 is anchored to the lever 54 at 58, and, extending through a hollow shaft 59 on which the holder 56 is mounted, passes through a sheath 60 and as its other end secured to a truck lever 61. Thus each time the truck lever 61 is depressed by cam 31 the stop pin 12 is swung up to the operative position shown in Figs. 9, 10 and 11. After the hank has been discharged the stop pin 12 falls back into its inoperative position in which it does not obstruct the action of placing a new hank on the holders 1, 2.

It is desirable that when in operative position the stop pin 12 should be capable of yielding slightly towards the holder 1 as the twisted hank is folded over it. For this purpose the hollow spindle 59 is rotatably mounted at 62, or the carrier 56 is rotatably mounted on the hollow spindle, for movement against the action of a spring 63 wound round the spindle.

This stop pin 12 also presses resiliently on the hank as the latter is being twisted so that the twisting and the doubling are effected under tension.

I claim:

1. A machine for twisting hanks, comprising two spaced holders for the reception of the hank, mounting means for said holders, means for effecting relative rotation between the holders to twist the hank and to produce a loop or eye in one end of the twisted hank, means for causing relative approach movement between the holders to double the twisted hank on itself to bring it end to end and for inserting the other end through the eye and means for discharging from the holders the twisted and doubled hank.
2. A machine according to claim 1, wherein the said means for causing relative approach movement operates by bringing the two holders into interfitting relationship.
3. A machine according to claim 2, having the holder for the said other end movable into a position in which it is disposed at the inside of the holder for the eye-end of the hank so that it enters the eye.
4. A machine according to claim 1, having a stop arranged to engage the twisted hank in the region of its mid length.
5. A machine according to claim 1, having a mechanism provided for varying at will the number of twists imparted to the hank.

6. A machine according to claim 1, having mechanism for adjusting the spacing between the two holders to accommodate them to hanks of differing sizes.

7. A machine according to claim 4, having the holder for said other end of the hank mounted for swinging movement about an axis alongside said stop to bring it into and out of proximity to the holder for the eye end.

8. A machine according to claim 5, wherein said mechanism comprises a releasable clutch for transmitting the hank-twisting drive, and pre-set means for releasing said clutch after a predetermined number of twists.

9. A machine according to claim 5, having mechanism for confining the number of twists to a whole number.

10. A machine according to claim 4, having means for shifting the stop to inoperative position.

11. A machine according to claim 4, having resilient mounting means for the stop for permitting it to yield as the hank is twisted.

12. A machine for twisting hanks, comprising two spaced holders for the reception of the un- 25

twisted hank, whereof one holder has a concave face presented towards the other and the latter is of finger-like form with a lateral protrusion spaced from its top, means for rotating the first holder to twist the hank, a stop for engaging the twisted hank in the region of its mid length, and a mounting for movement of the second holder to double the twisted hank over the stop and to pass along the concavity of the first holder and for thereby inserting an end of the twisted hank which is on the second holder onto an end of the twisted hank which is on the first holder.

13. A machine according to claim 4, having the said stop adapted to bear against and tension the hank during the twisting and doubling thereof.

EMILE BERNARD BATES.
